INVENTOR
Charles M. Mills
BY
Howard Freeman
ATTORNEY

UNITED STATES PATENT OFFICE.

CHARLES M. WILLS, OF ATLANTIC CITY, NEW JERSEY, ASSIGNOR TO THE AMERICAN TRANSOM CO. INC., OF PHILADELPHIA, PENNSYLVANIA.

VENTILATOR.

Application filed February 2, 1927. Serial No. 165,400.

My invention relates to ventilators, or similar devices, and refers particularly to devices of this character which are light-proof while allowing the passage of air there-

5 vice, thus operating with the device to produce a single unitary sound-proof, light-proof, ventilator allowing of the passage of air therethrough.

The advantages of the device of my invention will be evident upon a consideration of the accompanying drawings.

60 In the accompanying drawings illustrating modified forms of the device of my invention, similar parts are designated by similar numerals.

65 Figure 1 is a front view of one form of my device partly broken away for clearness of description and inserted within a transom opening.

70 Figure 2 is a side view of one form of my device, partly broken away for clearness of description.

Figure 3 is a cross-section through the line 3—3 of Figure 2.

75 Figure 4 is a cross-section through the line 4—4 of Figure 2.

Figure 5 is a cross-section through the line 5—5 of Figure 2.

Figure 6 is a cross-section through the line 6—6 of Figure 5.

80 Figure 7 is a vertical cross-section of a modified form of the bottom channel element.

85 The particular form of the device of my invention, shown in the accompanying drawings, comprises the two channel end pieces 10, 10 and the upper, or top, channel 11 and the lower, or bottom, channel 12. The upper channel 11 has a downwardly extended longitudinal tongue 13, and the lower channel 12 has an upwardly extended longitudinal tongue 14.

90 The outer faces of the device are formed of two plates 15, 15, each having a plurality of inwardly extended longitudinal louvers, or shutters, 16, 16, said shutters being stamped, or cut, out of the sheets and bent inwardly at such angles that air may pass through the openings 17, 17 but that the passage of light therethrough is prevented. The leaves, or shutters, 16, 16 abut upon the tongues 13 and 14, forming a light proof jointure therewith.

95 It will thus be seen that the tongues 13, 14 prevent the passage of light between the tops and bottoms of the louvers 16, 16 and the channels 11 and 12, which would other-

10 of this character, many of them are not so constructed as to absolutely prevent the passage of all light—a condition which is inoperative where the devices are employed for photographic or X-ray dark rooms in which 15 the admission of the slightest amount of light is highly objectionable and renders the device useless for the particular work described.

Devices of this character usually consist 20 of a plurality of over-lapping leaves, so positioned as to prevent the passage of a considerable amount of light while allowing the passage of air.

Devices of this construction have failed to 25 be absolute preventers of all light passage because of the practical impossibility of producing a complete and perfect abutment between the extremities of the leaves, or louvers, and the inner faces of the top and bottom of the supporting frame, and unless such abutment is perfect, light will be reflected through the interstices. This is particularly true in the most economical form 30 of ventilator, that in which the leaves are cut out of the sides of the device and turned inwardly. In this construction complete top and bottom abutment is impossible.

35 I have overcome this objectionable, and at times serious, feature of ventilators of this 40 character by placing a longitudinal tongue at each the top and the bottom of the device, the tongue resting upon the bottom plate, or top plate, and the leaves, or louvers, abutting upon the tongue.

45 In the device of my invention, it is immaterial if the leaves do not abut perfectly upon the top and bottom plates, as the longitudinal tongue of my device prevents the passage of light through the device even if 50 some does pass between the leaves and the frame.

Further, my device has a hinged sound-proof door carried by a side plate of the de-

wise occur because of the practical impossibility of making an absolutely light-proof jointure between the upper and lower edges of the louvers 16, 16 and the inner faces of 5 the channels 11 and 12.

In the modification shown in Figure 6, the tongue 14 is a separate piece fixedly attached to the channel 12, instead of being an integral part thereof, as shown in the 10 other drawings.

A practically sound-proof door 18 is hinged at 19, 19 to the lower portion of one of the side members 15. Positioned within the upper portion of the door is a spring 15 catch 21, the head 22 of the catch being capable of insertion within the locking member 23 carried by the upper portion of the side member 15, the cushion, or fabric covered knob 24 connected to the catch by means 20 of the connecting rod 25, movable through the opening 26, allows the catch to be operated.

It will be noted that the entire device, including both the ventilating elements and the 25 hinged sound-proof door is a single unit, capable of entire insertion within a transom opening, thus presenting a simple and an economical sound-proof, light-proof, air-admitting ventilator capable of being easily 30 and readily installed.

I do not limit myself to the particular size, shape, number, arrangement, or material, of parts, as shown and described, as these 35 are given simply as a means for clearly describing my invention.

What I claim is:—

1. In a ventilator, in combination, a frame, two side plates having a plurality of openings therein, a plurality of louvers extending 40 inwardly from the side plates and so positioned as to form air passages between the plate openings and to prevent vision therethrough and a tongue between the louvers extending longitudinally of the device 45 at the top and bottom thereof preventing the passage of light through the louver ends of the device.

2. In a ventilator, in combination, a frame, two side plates having a plurality of openings therein, a plurality of louvers extending 50 inwardly from the side plates and so positioned as to form air passages between the plate openings and to prevent vision therethrough, a tongue between the louvers 55 extending longitudinally of the device at the top and bottom thereof preventing the passage of light through the louver ends of the device and a hinged door carried by the device capable of extending across the face 60 thereof.

3. In a ventilator, in combination, a frame, two side plates having a plurality of openings therein, a plurality of louvers extending 65 inwardly from the side plates and so positioned as to form air passages between the plate openings and to prevent vision therethrough and a tongue abutting upon the louvers and positioned between the louvers extending longitudinally of the device at the top and bottom thereof preventing the 70 passage of light through the louver ends of the device.

4. In a ventilator, in combination, a frame, two side plates having a plurality of openings therein, a plurality of louvers extending 75 inwardly from the side plates and so positioned as to form air passages between the plate openings and to prevent vision therethrough, a tongue abutting upon the louvers and positioned between the louvers extending longitudinally of the device at the top and bottom thereof preventing the 80 passage of light through the louver ends of the device and a hinged door carried by the device capable of extending across the face 85 thereof.

5. In a ventilator, in combination, a frame comprising two end pieces, a top piece and a bottom piece, an inwardly extended tongue carried by the top piece and extending beyond the louver ends, an inwardly extended tongue carried by the bottom piece and extending beyond the louver ends, two spaced side plates carried by the frame, each side piece having a plurality of openings therein 95 and a plurality of inwardly extended louvers carried by each side plate upon its respective side of the tongues, the louvers and tongues being so positioned as to allow of the passage of air through the device and to prevent 100 vision therethrough.

6. In a ventilator, in combination, a frame comprising two end pieces, a top piece and a bottom piece, an inwardly extended tongue carried by the top piece and extending beyond the louver ends, an inwardly extended tongue carried by the bottom piece and extending beyond the louver ends, two spaced side plates carried by the frame, each side piece having a plurality of openings therein 110 and a plurality of inwardly extended louvers carried by each side plate abutting upon its respective side of the tongues, the louvers and tongues being so positioned as to allow of the passage of air through the device and to prevent 115 vision therethrough.

Signed at Philadelphia in the county of Philadelphia and State of Pennsylvania, this 24th day of January, 1927.

CHARLES M. WILLS.
